DIE CASTING MACHINE

Edward S. Bird, Worcester, Mass., assignor to
Reed-Prentice Corporation, Worcester, Mass.,
a corporation of Massachusetts

Application October 8, 1937, Serial No. 168,049

8 Claims.

(Cl. 22—2)

The present invention relates to a die casting machine and particularly to an arrangement of the passage by which the molten material is directed to the dies, the machine being especially useful in casting stereotype plates.

In the die casting of metals having a relatively low melting point, the machine provides for the distribution from a melting pot to the die through a relatively slender goose neck, in which, if the metal is not heated to a high temperature in the pot, there is a tendency for the material to solidify before it can reach the dies. One of the objects of the present invention is to provide an arrangement by which metal passing from the melting pot to the die may be kept at a suitable temperature by a provision for heating the material as it passes through the goose neck.

Where the material is to be cast in relatively thin plates, as in the casting of electrotype plates, if the material enters the dies through a relatively small nozzle, as in the usual construction, it is cooled before it can fill the entire opening in the die and a non-uniform plate, or a partially formed plate results. A further object of the present invention is to so arrange the goose neck and dies that the molten material will enter the dies in a relatively wide film and will be directed to the entire area of the die before the material solidifies or becomes too cool to fill all the interstices of the die.

Other and further objects and advantages of the invention will hereinafter more fully appear from the following description taken in connection with the accompanying drawings in which—

Fig. 1 is a sectional view through a die casting machine embodying the invention.

Fig. 2 is a plan view of the device of Fig. 1.

Fig. 3 is a sectional view along the line 3—3 of Fig. 1.

Fig. 4 is a sectional view along the line 4—4 of Fig. 1.

With reference first to Fig. 1, the machine comprises a base 1 which is suitably mounted on a foundation 2 which supports a burner 3, of well known construction, for heating the metal in the melting pot. The base is lined with suitable fire brick or other insulating material, and has an integral portion 1a to which the lower die is secured as by suitable bolts 4.

A melting pot 5, in the form of a cup, receives the metal to be used in the die casting and this metal is kept in a molten condition by the heat from the burner 3, above which the pot 5 is positioned. The melting pot has a projecting flange 6 which rests on the upper edge of the base 1

and is secured thereto by suitable bolts. The melting pot has an integral vertical cylinder 7, in which is located a piston 8. The upper edge of the cylinder has one or more notches 9 provided therein to allow the molten metal in the pot to flow into the cylinder when the piston 8 is elevated to uncover a part of the notch. The piston 8 is moved vertically by any suitable mechanism of well known construction, which may be a fluid actuated motor in the form of a cylinder and piston located above the melting pot.

From the lower end of the cylinder 7 the melting pot is provided with a passage 10 which extends diagonally upward toward the dies where the material is to be cast. This passage 10 forms a part of the goose neck, and as shown in Figs. 2 and 4, is substantially equal in width, at the bottom, to the diameter of the cylinder 7, and is relatively narrow vertically to define an elongated slot. As the passage 10 approaches the upper end thereof, the vertical dimension of the passage decreases substantially and the horizontal dimension increases substantially (see Fig. 3) to cause the molten metal passing through the goose neck to assume gradually a thinner and thinner web, which by reason of its thickness, can be heated rapidly by the hot gases from the burner.

As shown, the underside of the pot 5 beneath the passage extends diagonally upward substantially parallel to the passage and is spaced from the brickwork to allow hot gases to move upwardly directly beneath the passage for heating the metal therein. The upper end of the passage 10, which is a relatively long narrow slot, communicates with a similar shaped passage 11 in the lower die 12, this passage also extending diagonally upward in line with the passage 10. The passage 11, which at its connection with the passage 10, is similar in shape, continues to become more narrow vertically, and wider horizontally, to an open end 13 in the upper surface of the lower die. At this point the passage 11 is equal in width substantially to the width of the plate to be cast, and communicates with a passage 11' between the upper and lower dies which extend the entire width of the opening in the die. An arcuate recess 14 in the upper die 16 defines the upper surface of the passage 11' which is a continuation of the passage 11. The lower surface of the passage is defined by a hardened steel insert 15 in a recess 15' in the lower die. The upper surface of this insert cooperates with the recess 14 in defining the passage 11 which gradually decreases in thickness 55

until it is less than the general thickness of the plate to be cast. Thus, after the casting operation, the completed plate may be broken away from the material in the passage 11' along one edge of the plate where the hardened insert has substantially reduced the thickness of the casting.

10 The arrangement for separating the dies after the removal of cast plates and for holding the dies together during the casting operation may be of any suitable character, and may operate, if desired, in timed relation to the vertical movement of the piston 8. The timed relation allows the dies to remain together after the material has been forced between the dies for a sufficient time for the material to cool and solidify and pressure is then relieved by vertical movement of the piston 8 before the dies are separated. The upper die 16 is obviously mounted on a vertically movable head 17 for opening or closing the dies.

15 It will be noted that the melting pot cooperates with the lower die in forming a receptacle for molten metal in which the metal may be substantially the height of the open end of the passage 11 in the lower die, as shown in Fig. 1, so that metal in the passages 10 and 11 will remain in a molten condition throughout the entire length of the passage, especially when the heat from the burner which keeps the material in the cup molten is directed upwardly beneath the passages 10 and 11 for heating the latter.

20 The machine is especially useful in casting stereotype plates, and for this purpose, as shown in Fig. 1, the lower die 12 has a recess 18, Figs. 1 and 2, in which a matrix 19 is positioned, the latter then defining the lower surface of the opening 20 in the dies in which the stereotype plate is cast. The molten metal flows over the matrix and fills all the interstices in the dies under the influence of the pressure exerted by the piston 8. It will be apparent that, when the dies are closed, the adjacent surfaces of both upper and lower dies are in engagement around the entire periphery of the openings therein to confine the molten metal during the casting operation.

25 In order that the passage may retain its shape under heavy pressures of the molten metal in the passages 10 and 11, the passage 10 may have one or more integral webs 21 which are shaped to impede the flow of metal as little as possible.

30 In the operation of the machine, the piston 8 having been raised to allow molten metal to flow into the cylinder 7 and passages 10 and 11, the dies are brought together, as shown in Fig. 1. The piston 8 is then moved downwardly into the cylinder, forcing the molten metal through the passages 11 and 11' and into the opening in the dies above the matrix. Since the passage 11' is coextensive laterally with the opening in the dies the molten metal is directed between the dies in the form of a web and can thus be forced into all the small interstices of the matrix and upper die before it cools too much to flow.

35 From the foregoing it will be apparent that the present invention provides, in combination with a melting pot, a passage communicating with the pot and heated directly by the same burner that heats the pot. The passage which gradually becomes wider horizontally and thinner vertically, to assure the metal remaining sufficiently hot, has its upper end only slightly above the level of the metal in the pot and the passage is thus substantially filled with molten metal at all times. The passage allows the

metal to enter the dies above the matrix in a thin web as wide as the entire width of the matrix, and, in combination with the hardened insert 15, to provide for breaking the plate away from the hardened metal in the passage 11'. 5

I claim,

1. In a die casting machine, upper and lower dies defining therebetween a recess in which a relatively wide plate is cast, a plunger for forcing the material to be cast into the recess, and a 10 member having a passage providing a connection from the plunger to the dies, said passage gradually increasing in width toward the dies with the end of the passage adjacent the dies substantially as wide as the recess therein, the 15 lower of said dies having a passage communicating and in line with the passage in the member, said passage in the lower die extending from the underside to the top thereof.

2. In a die casting machine, upper and lower 20 dies defining therebetween a recess in which a relatively wide plate is cast, a plunger for forcing the material to be cast into the recess, a member having a passage providing a connection from the plunger to the dies, said passage gradually 25 increasing in width toward the dies with the end of the passage adjacent the dies substantially as wide as the recess therein, the lower of said dies having a passage communicating and in line with the passage in the member, said 30 passage in the lower die extending from the underside to the top thereof, and a hardened insert in one of said dies coextensive in length with the adjacent edge of the recess in which the material is cast, said insert being adjacent 35 to and extending parallel to the upper end of the passage in the lower die.

3. In a die casting machine, a base, cooperating dies, one of which is mounted on the base, a melting pot on the base, said pot having an upwardly slanting passage therein providing a connection from the pot to the dies, the die on the base having an upwardly slanting passage communicating with the passage in the melting pot and in line therewith, said passage in the die extending from the underside to the top of said die, with the upper end of the passage in the die substantially on the level with the normal level of the molten material in the pot. 45

4. In a die casting machine, a base, cooperating dies, one of which is mounted on the base, a melting pot on the base, said pot having a cylinder therein in which a plunger is slid able, and said melting pot having a passage therein extending upward from the lower end of the cylinder, the die on the base having a passage communicating with the upper end of the passage in the melting pot and in line therewith, said passage in the die extending from the underside to the top thereof, the upper end of the passage in the die being only slightly above the normal level of the molten material in the pot. 55

5. In a die casting machine, a base, cooperating dies, one of which is mounted on the base, a melting pot on the base, said pot having a cylinder therein in which a plunger is slid able, and said melting pot having a passage therein extending upward from the lower end of the cylinder, the die on the base having a passage communicating with the upper end of the passage in the melting pot and in line therewith, said passage in the die extending from the underside to the top thereof, said passage in the pot becoming gradually wider and thinner as it approaches its 70 75

upper end, and reinforcing webs in the passage to prevent distortion thereof.

6. In a die casting machine, a base, cooperating dies, one of which is mounted on the base, a melting pot on the base, said pot having a cylinder therein in which a plunger is slideable, and said melting pot having a passage therein extending upward from the lower end of the cylinder, the die on the base having a passage 10 communicating with the upper end of the passage in the melting pot and in line therewith, said passage in the die extending from the underside to the top thereof, the upper end of the passage being partially defined by an insert 15 in one of the dies, said insert being substantially equal in length to the width of the recess in the dies in which the material is cast.

7. In a die casting machine, a base, cooperating dies, one of which is mounted on the base, a melting pot on the base, said pot having a cylinder 20 therein in which a plunger is slideable, and said melting pot having a passage therein extending upward from the lower end of the cylinder, the die on the base having a passage communicating with the upper end of the passage in 25 the melting pot and in line therewith, said pas-

sage in the die extending from the underside to the top thereof, the upper end of the passage being defined by a hardened insert in one of the dies and an arcuate recess in the other die, with the extreme end of the passage thinner 5 than the general thickness of the plate to be cast.

8. In a die casting machine, a base, upper and lower dies defining a recess therebetween, the lower die being mounted on the base, a melting 10 pot on the base, said pot having a cylinder therein in which a plunger is slideable, said pot having a passage providing a connection from the cylinder to the lower die, the lower die having a passage providing a connection from the upper end 15 of the passage in the melting pot to the recess in the dies, said passage in the die extending from the underside to the top thereof, said lower die having a recess to receive a matrix, an insert 20 in the lower die at the edge of said recess at least as long as the width of the recess, the upper surface of the insert being in line with the upper end of the passage in the lower die and being coextensive therewith, to form a continuation of the passage. 25
